PROCESS OF DISTILLING MINERAL OIL UNDER A HIGH VACUUM

Application filed February 27, 1926. Serial No. 91,048.

In an application filed by me June 19, 1925, Serial No. 38,184, of which this application is in part a continuation, I set forth an apparatus for the continuous distillation of oil under a high vacuum. Included in the apparatus is a series of stills. These stills and the rest of the oil and oil vapor system are under a high vacuum. It is essential that there shall be no leakage whatever into this system. The success of the process depends not merely on the maintenance of the vacuum at a predetermined degree. If this could suffice, continuously acting air pumps would maintain the vacuum notwithstanding slight air leakage into the system. It is important, however, to prevent any circulation of even extremely rarified air through the system, which circulation could occur in case of any leakage. The vacuum air pumps should be relied upon, therefore, only to exhaust air from the system at the start of the process and to continuously exhaust from the system permanent gases that form during the distilling process and which, if allowed to accumulate, would build up pressure, but which, to the extent that they are present and circulate through the system, do not have the objectionable oxidizing effect of air.

This air tight closure of the oil system may be effected in part by making air tight all joints, valves, removable covers, and bearings; but unless some means be devised to prevent it, the oil that is pumped from the source of supply to the first still of the series will carry with it some air. The object of the invention forming the subject matter of this application is to prevent air being pumped in with the oil.

In the drawings, which show a preferred embodiment of the invention—

Fig. 1 is a diagram of the first still of the series and the means for supplying oil thereto.

Fig. 2 is a detail view of the pressure regulating valve of Fig. 1.

The still tank *a*, having a residual oil outlet *x* and oil vapor outlets *y* to a condenser *z*, is supplied with oil from the supply pipe *b*. On the pipe *b* is a valve *c* which regulates the rate of flow of oil to the still. A meter *d* and a pump *e* are interposed in the pipe *b*.

Around the pump is a shunt circuit pipe *f* provided with a pressure relief valve *g*, which is shown in detail in Fig. 2. This valve, however, may be of any known or convenient construction. It is set to open at any superatmospheric pressure desired.

When the pump *e* is first started, valve *c* is closed, thus forcing the oil around the pump through the return pipe *f* and immediately building up a pressure sufficient to open valve *g*. Valve *c* is now opened until the meter indicates the rate of flow desired. Pump *e* continuously delivers oil at a higher rate of flow than the flow through valve *c*, thereby maintaining circulation through pipe *f* and holding the pressure that has been built up.

With a constant superatmospheric pressure in the pipe line and with the oil at the source of supply at atmospheric pressure, no air can be drawn with the oil, through the pipe *b* into tank *a*.

What I claim is:

The process of supplying oil from a source of supply to a still under high vacuum while preventing the admission of air with the oil, which comprises pumping oil from a source of supply to the still at a rate constantly exceeding the rate at which it is desired to deliver oil to the still, so throttling the flow of oil from the pump to the still as to maintain a substantially constant rate of flow of oil to the still constantly below the rate at which the oil is pumped, maintaining in the supply pipe between said point of throttling and the pump a pressure constantly above the pressure between the pump and the source of supply, maintaining a constant return flow of oil from a point between the pump and the point of throttling to a point in the oil supply behind the pump, and regulating the pressure in the oil supply between the pump and the point of throttling by varying the rate of said return flow of oil.

In testimony of which invention, I have hereunto set my hand, at Philadelphia, Pennsylvania, on this 19th day of February, 1926.

ARTHUR E. PEW, JR.
